UNITED STATES PATENT OFFICE.

BENJAMIN D. BARROW, OF DETROIT, MICHIGAN, ASSIGNOR TO PACKARD MOTOR CAR COMPANY, OF DETROIT, MICHIGAN, A CORPORATION OF MICHIGAN.

HYDROCARBON-MOTOR.

1,321,080.

Specification of Letters Patent. Patented Nov. 11, 1919.

Application filed March 19, 1917. Serial No. 155,856.

To all whom it may concern:

Be it known that I, BENJAMIN D. BARROW, a citizen of the United States, and resident of Detroit, Wayne county, State of Michigan, have invented certain new and useful Improvements in Hydrocarbon-Motors, of which the following is a specification.

This invention relates to hydrocarbon motors and particularly to cylinder construction.

One of the objects of the invention is to produce a built up cylinder structure of a commercially practical form and one in which lightness is particularly noticeable.

Another object of the invention is to produce a plural cylinder structure in which several cylinder elements are connected by an attached jacket.

Another object of the invention is to form a plural cylinder structure in which adjacent cylinder elements are connected by an expansion piece welded to adjacent parts of the cylinder and by a jacket connected to both cylinder elements.

Another object of the invention is to form a cylinder structure in which the cylinder elements may be made of steel forgings and the jacket of sheet steel welded on to the cylinder elements.

Another object of the invention is to form a plural cylinder structure in which the cylinder elements are arranged close together and provided with a sheet metal jacket which does not pass between the cylinders but leaves a single water space between adjacent cylinder walls.

Another object of the invention is to provide a plurality of cylinder elements with a built up steel jacket of novel construction.

Other objects of the invention will appear from the following description taken in connection with the drawings which form a part of this specification and in which—

Figure 1 is a side elevation of a cylinder structure built according to this invention;

Fig. 2 is a sectional view on the line 2—2 of Fig. 1 looking upwardly as shown by the arrows;

Fig. 3 is an enlarged vertical sectional view of a lower portion of two adjacent cylinders.

Fig. 4 is an enlarged perspective view of

a connecting piece used between adjacent cylinders, and

Fig. 5 is a perspective view of the lower portion of a cylinder element as it appears before the attachment of the jacket.

Referring to the drawings, 10, represents a cylinder structure built in accordance with this invention. Three cylinders are shown in this structure but it will be understood that any desired number of cylinders may be grouped within reasonable limits.

The cylinder elements are indicated at 11 and each of them is formed with an attaching flange 12 at its lower extremity and projections 13 and 14 near its upper end, in which are the various cylinder ports and other openings. Each of the cylinder elements is also formed with a flange 15 a short distance above its lower end, this flange being preferably of L shape which provides a downwardly extending skirt 16 around the periphery of the flange. Both of the flanges 12 and 15 are cut away somewhat or flattened off along one side of the cylinder so that two cylinders may set closer together without flange interference and in the case of three cylinders the center cylinder is cut away on two opposite sides. These cut away flat parts are indicated at 17 and 18 respectively, on the drawings, being particularly shown in Fig. 5.

The tops of the cylinder elements are connected and covered by a cover piece 19 which may be welded or otherwise secured to the cylinder around the projections 13 and cylinder jacket 20 which surrounds the several adjacent cylinders. This jacket 20 is preferably made of sheet steel and it may be in a single piece or several pieces welded or otherwise joined together and as shown it surrounds the three cylinders and is connected to the flanges 15 of each of the cylinders by welding its lower edge to the skirts 16 of said flanges.

When two adjacent cylinders are arranged in the close proximity shown in the drawings it is desirable to have but a single jacket of water between them and the present construction contemplates this arrangement. The jacket 20 follows the cylinder wall part way between the adjacent cylinders and then curves at about right angles 105 to form the jacket of the next cylinder.

This leaves an open space at the bottom of the jackets between the cylinders, which space is filled by a piece 21 which is secured as by welding to the adjacent flat parts 18 5 of the flanges 15. This piece 21 is shown as of inverted U form and its ends are welded to adjacent parts of the jacket 20 thereby completing the inclosure of the cylinders to permit of cooling them by circulating water through the chambers or 10 15 enclosed spaces formed by the jackets.

It will be understood that in building up this cylinder structure the pieces 21 are first secured to the respective adjacent cylinders 15 and the jacket 20 is then welded into position around the cylinders and to the flanges 15 and the pieces 21. By this construction more or less flexibility of the structure is attained and not only may the cylinder elements 20 25 be properly positioned in exact relation to each other upon the crank case or other support to which they may be bolted, but any other slight expansion or contraction between the cylinder elements 25 30 may take place without in any way injuring or jeopardizing the construction of the jacket parts.

While but one form of the invention is shown and described it will be understood 30 that other forms may be made without departing from the invention as set forth in the claims.

Having thus described my invention, what I claim and desire to secure by Letters

35 Patent is:

1. A motor cylinder structure comprising a plurality of cylinders each having an attaching flange at the lower end and a peripheral flange above said attaching flange, 40 one piece expansion pieces secured between the adjacent peripheral flanges, and a jacket surrounding said cylinders and secured to said expansion pieces and to said peripheral flanges.

45 2. A motor cylinder structure comprising a plurality of individual cylinders, and one

piece expansion strips of substantially inverted U shape welded therebetween adjacent to the lower ends.

3. A motor cylinder structure comprising 50 a plurality of cylinders each having a peripheral flange adjacent to the lower end thereof, each flange being flattened on the side next another cylinder to form adjacent parallel faced flanges, said flanges having 55 downwardly turned skirts forming welding faces, and a jacket surrounding said cylinders and welded to said flanges.

4. A motor cylinder structure comprising 60 a plurality of cylinders each having a peripheral flange adjacent to the lower end thereof, each flange being flattened on the side next another cylinder to permit close arrangement of cylinders, said flanges having 65 downwardly turned skirts forming welding faces, one piece expansion pieces of substantially inverted U shape welded to the flattened parts of said flanges, and an outer jacket surrounding said cylinders and 70 welded at the lower edge thereof to the circular portion of said flanges and to the ends of said expansion pieces.

5. A motor cylinder structure comprising 75 a plurality of cylinders, a top plate covering the tops of said cylinders, a side jacket surrounding said cylinders, and expansion strips joining said cylinders together, said top plate, side jacket and expansion strips being joined so as to completely incase the cylinders.

6. A hydrocarbon motor comprising 80 a plurality of cylinders each having a peripheral flange, a top plate covering the tops of said cylinders, a side jacket surrounding said cylinders, and expansion strips welded 85 to said flanges and joining said cylinders together, said top plate, side jacket and expansion strips being joined so as to completely incase the cylinders.

In testimony whereof I affix my signature.

BENJAMIN D. BARROW.
